ROLLING DOOR CONSTRUCTION

Nathan Michelman, Brooklyn, N. Y.

Application August 12, 1944, Serial No. 549,230

17 Claims. (Cl. 160—310)

This invention relates to rolling doors adapted to be wound upon a drum located at the head of the doorway and to be unwound therefrom, and is more specifically directed to the provision of improved driving mechanisms for such doors.

Rolling doors of considerable length and weight, such as are employed in factories, garages or the like, are generally provided with a driving mechanism operated by an electric motor, to facilitate the raising and lowering of the door. Since, however, such power drive may occasionally break down, a manually operable driving mechanism is also incorporated in the structure. Usually, the two driving mechanisms are entirely independent and are operated through separate gearing means. The resulting structure is therefore complicated and expensive to manufacture. Furthermore, the usual constructions lack suitable means for automatically controlling the operation of the electric motor and for braking the door at the end of its downward or upward movement.

It is therefore an object of the invention to provide a rolling door structure comprising power driving means and hand driving means adapted to operate the door through a common set of gears, which is selectively connectible to either one of said driving means, thereby considerably simplifying the construction of the door and reducing the cost of manufacture thereof.

It is a further object of the invention to provide a structure of the aforementioned character, wherein the shifting from power to hand operation, and vice versa, may be effected in a single operation, through the manipulation of only one element of the structure.

Another object of the invention is to provide means for automatically shutting off the electric motor at the end of the downward or of the upward movement of the door, said means being controlled by elements associated with the door shaft.

Still another object of the invention is to provide means for braking the door shaft that are automatically actuated to braking position simultaneously with the shutting off of the electric motor effected as aforementioned.

These and other objects will become apparent in the following description of the invention illustrated in the drawings, wherein:

Fig. 1 is a front elevational view of the power and hand drive mechanisms for rolling doors according to the invention, and of the braking mechanism associated therewith.

Fig. 2 is a side elevational view of the structure of Fig. 1.

Fig. 3 is a fragmentary front elevational view of the device of Fig. 1 illustrating details of the braking mechanism.

5 Fig. 4 is a top plan view of the structure shown in Fig. 3.

Fig. 5 is a front elevation similar to the view of Fig. 1, with parts of the structure removed to illustrate the gearing of the device.

10 Fig. 6 is a horizontal sectional view on the line 6—6 of Fig. 5.

Fig. 7 is a vertical sectional view on line 7—7 of Fig. 1, in the direction of the arrows.

15 Fig. 8 is an enlarged top plan view of the means for controlling the electric motor for the door driving mechanism.

Fig. 9 is a side elevational view of the structure of Fig. 8.

20 Fig. 10 is a front elevation of the same structure illustrating the construction of the limit switches associated therewith.

Fig. 11 is a rear elevation of the same structure.

25 Fig. 12 is a front elevational view illustrating a different embodiment of the power and hand drive mechanisms.

Fig. 13 is a horizontal section on line 13—13 of Fig. 12, showing a modified clutch mechanism employed in the embodiment of Fig. 12.

30 Fig. 14 is an enlarged fragmentary view, partly in section, of a different embodiment of braking mechanism.

Fig. 15 is a perspective view of one of the split 35 rings of Fig. 14 forming part of the braking mechanism.

Fig. 16 is a front elevational view illustrating still another embodiment of braking means.

Fig. 17 is a side elevational view, partly in section along line 17—17 of Fig. 16.

40 Fig. 18 is an enlarged fragmentary horizontal section and Fig. 19 is an enlarged fragmentary vertical section, on lines 18—18 and 19—19 of Fig. 16, respectively.

45 Referring now in detail to the drawings, numeral 10 indicates the shaft of a rolling door suitably supported at the head of the doorway and carrying, for rotation therewith, a conventional coaxial drum 11, to which there is secured, as at 12, the end of a flexible door or curtain 14 adapted to be wound upon the drum 11 and formed of a plurality of sections or slats interconnected in the usual manner. Suitable counterbalancing mechanism (not shown) is provided 50 for the assembly.

The end of the shaft 10 carries, for rotation therewith, a hollow shaft 15 keyed thereto, as at 16, which extends through a bearing 17 of a supporting plate 18, fastened to the wall laterally of the door, and through a bearing 20 of further fixed plate 22. The hollow shaft 15 has an end portion 24, which is threaded for the purpose that will become hereafter apparent. A plate or covering 25 is fastened to the plate 22, as by means of screws or bolts 26, and has a bearing 27 through which the hollow shaft 15 also extends. The covering 25 cooperates with the plate 22 to form a casing for a gear train through which the shaft 15 and the door shaft 10 are driven, in the manner that will now be described.

A shaft 28 is freely mounted in a pair of bearings 29, 30, provided in the plate 22 and covering 25, respectively, below the shaft 15, and extends outwardly of the covering 25. Fastened to the shaft 28, at the rear of bearing 29, is a stop collar 31, and between the bearings 29, 30, there is a pinion 32 likewise fastened to the shaft 28. This pinion meshes with a spur gear 34 fast on a short shaft 35 which is rotatable in further bearings 36, 37 formed on the plate 22 and the cover 25, respectively.

The shaft 35 also has, fast thereon, a pinion 38, which in turn meshes with another spur gear 39 secured, as by bolts 40, to a flange 41 which may be integral with the shaft 15. As will be apparent, rotation of the lower shaft 28 will result in the rotation of the shaft 15, and therefore of the door shaft 10, through the gear couplings described, at a greatly reduced rate relative to the shaft 28.

The shaft 28 carries a pulley 42 loosely mounted thereon, which is grooved to receive a V-belt, or the like, connecting said pulley to a smaller pulley 43 of a reversible electric motor 44. The hub of the pulley 42 is provided with teeth 45, and longitudinal displacement of the pulley on the shaft 28 is prevented by the collar 46 suitably fastened to the shaft and received in a recess of the hub of the pulley. The assembly described constitutes the power drive for the door shaft 10, and is inoperative as long as the pulley 42 is free to rotate on the shaft 28; to render the assembly operative, whenever desired, a suitable means or clutch device is provided to drivingly associate the shaft 28 with the pulley 42, as will be hereafter described.

The ratio of the complex of pulleys 43-42 and gear couplings 39-38-34-32 is such that, when the assembly is rendered operative, the speed of rotation of shaft 10 will be of an order suitable for proper operation of the door. For instance, with a motor speed of 1800 revolutions P. M. the speed of the shaft 10 will be approximately 4 revolutions P. M. whereby a conveniently slow movement of the door will be obtained. Such a considerable reduction has the further advantage of permitting the use of an electric motor of a comparatively low power, with a corresponding reduction in the cost of the device.

The construction also comprises means for hand operation of the door shaft 10. Referring now particularly to Figs. 5 and 6, it will be observed that a shaft 48 is journalled in bearings of the plate 22 and covering 25, as at 49, 50, and has fastened thereto a stop collar 51 abutting against the bearing 49 rearwardly thereof; a pinion 52 is fast on the shaft 48 between the bearings 49, 50, and meshes directly with the gear 39 fastened to the hollow shaft 15. On a portion of the shaft 48 extending outwardly from the covering 25 there

is freely mounted a sprocket wheel 53, which carries a continuous chain 54 extending downwardly to a position within reach of the operator, when the assembly is mounted at the head of the doorway.

The hub of sprocket wheel 53 is provided with teeth 55, and is maintained in fixed longitudinal position relative to the shaft 48 by means of a stop collar 56, which is fastened to the shaft and is received within a suitable recess formed in the hub. The assembly just described constitutes the hand drive for the door shaft 10, and is manifestly inoperative as long as the sprocket wheel 53 is free to rotate relative to the shaft 48. To render selectively operative either the power drive or the hand drive, the following mechanism is provided.

A clutch 58 is mounted, for rotation therewith, on the outwardly extending portion of the shaft 28 of the power drive assembly, the shaft being suitably splined, as at 59, to permit longitudinal movement thereon of the clutch 58 between the pulley 42 and a stop collar 60 fastened to the end of the shaft. The clutch 58 grooved as shown at 61 is provided with teeth 62 opposite the teeth 45 of the hub of pulley 42 and adapted to engage these latter for the purpose that will hereafter become apparent.

A further clutch 64 is similarly mounted on the shaft 48 of the hand drive mechanism, for conjoint rotation therewith and longitudinal movement therealong, and is likewise provided with teeth 65, opposite teeth 55 of the hub of sprocket wheel 53. Said clutch is also grooved as at 66 (see Fig. 2). A rod 68 is rotatably supported, in fixed vertical position, by brackets 69, 70, 71 that are suitably secured to the plate 22, the rod extending downwardly as far as necessary to locate a knob 72, carried at the lower end thereof within reach of the operator. Fast on the rod 68 are a pair of spaced members 74, 75 extending in opposite directions laterally of the rod and formed with forked end portions 76, 77, respectively, provided with depending studs 78, 79 that project into the grooves 61 and 66 of the clutches 58 and 64.

As will be apparent, by manipulating the knob 72 to rotate the rod 68 in opposite directions, the forks 76 and 77 may be swung to reciprocate the associated clutches 58 and 64 on their shafts 28 and 48, thereby bringing the teeth 61 and 65 thereof into engagement with the teeth 45 and 55 of the pulley 42 and sprocket wheel 53, or disengaging the same therefrom. Obviously, when the teeth are interengaged, rotation of the pulley 42 or of the sprocket wheel 53 will cause rotation of the respective shaft 28 or 48 through the associated clutch 58 or 64 which is mounted on its shaft for rotation therewith, and therefore the power drive or the hand drive mechanism will be rendered operative to drive the door shaft 10 and to raise or lower the rolling door according to the direction of rotation of the shaft.

The forked members 74, 75, which extend in opposite directions, are angularly staggered, on the rod 68, by such an amount that, when the clutch 61 of the power drive mechanism is moved into the position in which it engages the teeth 70 of pulley 42, the clutch 64 of the hand drive mechanism is simultaneously disengaged from the teeth of the sprocket wheel 53, and vice versa. Normally, the clutch 61 will be in engagement with the teeth of pulley 42, when the door is being raised or lowered, since the power

drive is normally used and the hand drive mechanism is provided only for emergency cases. The members 74 and 75 may also have a neutral position wherein neither of the clutches is operatively connected to the respective pulley and sprocket wheel, and both the power and the hand drive devices will then be inoperative.

As will be readily seen, both power and hand operation of the door is effected through the gear 39 common to both mechanisms, with a considerable simplification of the structure as compared with the devices of the prior art, and the shifting from power to hand operation, and vice versa, is accomplished in a single operation through the manipulation of only one element of the structure.

As will be observed from Figs. 5 and 6, the casing of the driving mechanism also embodies a pair of bearings 80, 81, disposed at the left of gear 39 symmetrically with the bearings 49, 50. The shaft 48 of the hand drive may be mounted in said bearings 80, 81, so that the hand drive assembly may be shifted to the left of the structure whenever it is preferable to have the assembly in such a position.

Figs. 12 and 13 illustrate a modification of the driving means hereinbefore described, in which the construction of the mechanism is still further simplified.

In this embodiment, the gearing of the power drive described remains unchanged, but a longer shaft 82 is substituted for the shaft 28 (see Fig. 13). The sprocket wheel 53 of the hand drive mechanism carrying the chain 54 is freely mounted on the forward portion of the shaft 82 and is prevented from longitudinally moving along the shaft by the collar 83, secured at the end of the shaft, and the collar 84 received within a recess of the hub of the sprocket wheel. The position of this latter is inverted with respect to the showing of Fig. 6 so that the teeth 55 thereof face the teeth 45 of the pulley 42.

A clutch 85 is mounted on a suitably splined portion of the shaft 82, as shown at 86, between the sprocket wheel 53 and the pulley 42, for rotation with the shaft and reciprocation thereon. Said clutch is provided with teeth 87, 88 projecting therefrom in opposite directions, and adapted to engage either the teeth 45 of the pulley 42 or the teeth 55 of the sprocket wheel 53 in the reciprocation of the clutch along the shaft 82. The clutch is centrally grooved, as shown at 89, to receive the studs of the fork 76 of the member 74 which is mounted on the rod 68 as in the embodiment previously described.

As will be readily understood, the rotation of the rod 68 brought about by the manipulation of the knob 72, as hereinbefore explained, will therefore longitudinally displace the clutch 85 along the shaft 82, and cause the teeth 87 of the clutch to engage the teeth 45 of the pulley 42 while simultaneously disengaging the teeth 88 from the teeth 55 of the sprocket wheel 53, or vice versa. In the first case, the pulley 42 will thus become operatively connected to the shaft 82, and the motor 44 will be enabled to drive the door shaft 10 through the gear train hereinbefore described, while the sprocket wheel 53 will idle on the shaft 82; in the second case, the sprocket wheel will be operatively connected to the shaft and, through the same train of gears, to the door shaft 10 for hand driving thereof, while the pulley 42 will idle on the shaft.

Reference will now be had particularly to Figs. 8 to 11, which illustrate the means for auto-

matically shutting off the electric motor 44 at the end of the upward or downward movement of the rolling door.

An internally threaded collar 90 is mounted on the threaded end portion 24 of the shaft 15 fastened to the door shaft 10, and has an upwardly extending portion 91 forming a bushing slidably mounted on a stationary shaft 92. This latter is fastened to aforementioned covering 25. The collar 90 is therefore prevented from rotating with the threaded portion 24 of the shaft 15 during rotation of this latter, and is caused to travel therealong in opposite directions according to the direction of rotation of the shaft. The aforementioned extension 91 of the collar is provided with a pair of projecting cams 93, 94 having identical profile, the purpose whereof will become later apparent.

A further stationary shaft 95 is secured to the covering 25 above the shaft 92, and carries, pivotally mounted thereon intermediate their ends, a pair of levers 96, 97, at the rear ends whereof there are formed cam surfaces 98 and 99. Said cam surfaces have an identical profile and are adapted to be engaged by the cams 93, 94 of the collar 90 during the reciprocation of this latter.

The levers 96, 97 are provided, at their forward end, with downwardly extending depending studs 100 and are associated with a pair of switches 102, 103 (hereinafter referred to as "limit switches" by reason of their function). Each limit switch comprises an element 104 slidable therein and urged by a spring 105 to an upward position in which a contact element 106 closes the switch, as shown in Fig. 10 and the studs 100 of the levers 96, 97 rest on said elements 104 of the limit switches. As will be apparent, whenever one of the cams 93, 94 engages the cam surface of the respective lever, this latter will be rocked and the stud 100 thereof will depress the member 104 of the associated switch to a lowermost position, to displace the contact element 106 and the various parts being returned to their initial position upon disengagement of the cam 45 from the cooperating cam surface of the lever.

The electric motor 44 is reversible, and either the limit switch 102 or the limit switch 103 is closed at any given time, due to the arrangement of the cams and levers illustrated (see particularly Fig. 11). In such condition of the switches, the motor can always be started, and the direction of its rotation will depend upon which one of the switches is closed at the time. The opening of the switch initially closed, following the engagement of one of the cams with the lever associated therewith, will shut off the motor, but, since in the meantime the other switch will have closed, the motor can be started again in the reverse direction. The electric circuits required for such operation of the motor form no part of the invention and may be conventional, and therefore will not be described.

Let us now assume that the door shaft 10, as seen in Fig. 10, has been rotated through the gearing described, in a counterclockwise direction, to lower the door, and the motor has been shut off by the opening of the limit switch 103. Cam 93 is now clear of cam surface 98 of lever 96 and switch 102 is closed, whereby the motor 70 may be started to drive the door shaft 10 in a clockwise direction and raise the door. In the ensuing clockwise rotation of the threaded portion 24 of shaft 15, collar 90 is caused to travel towards the left, as indicated by the arrow in Fig. 11, until cam 93 engages cam surface 98

of lever 96 and rocks this latter, whereupon the member 104 of the switch 102 is moved downwardly to open the switch, and the motor is shut off. The pitch of the thread of shaft portion 24 is such that collar 90 will travel the distance necessary for bringing cam 93 into engagement with cam surface 98 in the time required for shaft 10 to complete a number of revolutions sufficient for fully raising the door, in the present embodiment four revolutions. Manifestly, during the operation described cam 94 has become disengaged from cam surface 99, and the spring 105 of limit switch 103 has closed this latter, simultaneously returning lever 97 to its initial position, whereby the motor may be started again in a reverse direction to rotate the door shaft counterclockwise and lower the door.

Reference will now be had particularly to Figs. 1 to 4 which illustrate one embodiment of braking means provided in the structure described. Pulley 42 mounted on the shaft 28 carries a brake drum 110, which is surrounded by brake elements 111, 112 pivoted at one end thereof, as at 113, and normally urged into frictional engagement with the surface of the drum by a spring 114 connecting the opposite ends of said brake elements. A lever 115 is pivotally mounted on a bracket 116 secured to the plate 22, and is formed with a transverse cam portion 117 engaging extensions 118, 119 of the brake elements 111, 112.

A link 120 connects the end of lever 115 to one end of a lever 121, which is pivoted to the covering 25, as at 122, and pivotally carries at its other end a link 123 connected to a member 124 associated with an electro-magnet 125. When the motor 44 is inoperative, the electro-magnet 125 is not energized and the assembly described is in the position illustrated in Fig. 1 wherein the spring 114 is shown to maintain the brake elements 111, 112 in engagement with the surface of the drum 110 and the door shaft is therefore braked.

The electro-magnet 125 is energized upon the starting of the motor 44, irrespective of the direction of rotation of this latter, suitable electrical connections being provided for this purpose. The member 124 is therefore caused to move upwardly, lever 122 is rocked, link 121 is moved downwardly and the pivoted lever 115 is rotated, to cause the cam portion 117 thereof to move brake elements 111, 112 away from the drum 110, in opposition to the spring 114. In this manner, the drum is released and the pulley 42 is permitted to drive the door shaft as hereinbefore described. Concurrently with the shutting off of the motor, the electro-magnet 125 is again de-energized, whereupon the spring 114 is allowed to bring again the brake elements 111, 112 into frictional engagement with the drum 110, to brake the pulley 42 and prevent any further movement of the door shaft 10.

An entirely different construction of the braking means is illustrated in Figs. 14 and 15. In this embodiment there are provided a pair of internally threaded rings 128, 128a that are directly mounted on the threaded end portion 24 of the shaft 15. The rings are cut in a plane perpendicular to the axis thereof, the cut extending through the threads of the rings in the manner illustrated in Fig. 15, to form substantially resilient ring portions 130, 131 and 130a, 131a. Bolts 132 force such portions of the rings toward one another and cause the thread portions incorporated therein to clamp therebetween, the corresponding threads of the shaft portion 24, thereby locking the rings in fixed position.

The collar 90 is mounted on said threaded shaft portion 24 intermediate the rings 128, 128a and the distance between these latter is equal to the space travelled by the collar in its reciprocatory movement described. Therefore, at the end of each stroke the collar 90 will operate one of the limit switches 102, 103, through the action of its cams 93, 94 to shut off the motor, and simultaneously engage with one of its flat lateral faces the opposed flat face of one of the rings, thereby positively preventing any further rotation of the door shaft.

Figs. 16 to 19 illustrate a further embodiment of brake mechanism, which is particularly suitable for use in rolling doors of the character described of comparatively light construction.

Forked members 135, 136 are connected, as shown at 137, 138, respectively, to the levers 96, 97 that control the operation of the motor 44, and extend vertically downwardly therefrom, movement of the members relative to the levers being prevented by the interengagement of the upper forked end thereof with complementary enlarged portions 139 of the levers. The forked members are threaded at their lower end, as shown at 140, 141 in Fig. 19, to rigidly mount members 142, 143 partially extending into a U-shaped member or channel 144, which is slightly wider than the members to permit a limited displacement of the channel relative to these latter for a purpose that will become hereafter apparent.

The channel 144 is provided with a downward extension 145 to which there is rigidly secured a brake element 146 which is pivotally connected to the plate 22, as at 147, and carries a brake shoe 148 adapted to frictionally engage the drum 110 of the pulley 42. A brace 149 is fastened to the channel extension 145 and to the brake element 146, to provide a rigid structure.

A coil spring 150 connected to a bracket 151 carried by the cover 25 and to the channel extension 145, normally causes the brake element 145 to swing about its pivot 147 away from the drum 110, to release the pulley 43, the swinging movement being limited to a minimum sufficient to release the pulley by the engagement of the inner surface of the channel 144 with the members 142, 143 partially extending thereinto, as aforesaid.

Compression springs 153, respectively mounted within recesses 154, 155 of the members 142, 143, rest upon the bottom wall of the channel 144. As will be apparent, when one of the levers 96, 97, for instance the lever 96, is rocked to move its forward end to a lowermost position and shut off the motor 44 in the manner hereinbefore described, the associated forked member 135 and the member 142 will move downwardly, and the respective spring 153 will be compressed, as illustrated in Figs. 16 and 19, to urge the pivoted brake element 146 toward the drum 110 and the brake shoe 148 into frictional engagement therewith in opposition to the spring 150, thereby braking the pulley 42. While this action is sufficient to overcome the inertia of the rotating elements and to arrest immediately the pulley when the motor is shut off, the strength of the spring 153 is, however, not such as to prevent rotation 70 of the pulley under the driving action of the motor, so that the door shaft may be rotated in a reverse direction by starting again the motor while the brake mechanism is still in the operative position described. Manifestly, in the continued rotation of the door shaft, the forward

end of the lever 96 will move upwardly lifting the forked member 135 and the member 142 associated therewith, whereby the brake elements may be returned by the spring 150 to their inoperative normal position described. Concurrently, the lever 97 is gradually rocked until it reaches the position in which it becomes effective to shut off the motor and to simultaneously operate again the brake through its forked member 136 and associated member 143 and spring 153.

It will be understood that changes and modifications may be made in the structures described and illustrated in the drawings without departing from the spirit of the invention or exceeding the scope of the claims.

I claim:

1. A driving mechanism for rolling doors comprising a rotatable door shaft, a gear train drivingly associated with said shaft, an electric motor, manually operable driving means, said motor and said manually operable driving means being operatively connectable to said gear train to drive said door shaft therethrough, and means effective to operatively connect the electric motor to the gear train, while simultaneously disconnecting the manually operable driving means therefrom, and to operatively connect these latter means to the gear train while simultaneously disconnecting the electric motor therefrom.

2. A driving mechanism for rolling doors comprising a rotatable door shaft, a speed reducing gear train drivingly associated with said door shaft, an electric motor, a pulley driven by said motor, a manually operable driving wheel, said pulley and said wheel being operatively connectable to said gear train to drive said door shaft at a reduced speed, and means effective to operatively connect the pulley to the gear train, while simultaneously disconnecting the manually operable wheel therefrom, and to operatively connect this latter to the gear train while simultaneously disconnecting the pulley therefrom.

3. A driving mechanism for rolling doors, comprising a rotatable door shaft, a speed reducing gear train drivingly associated with said door shaft, an electric motor, a second rotatable shaft for driving said gear train, a third rotatable shaft drivingly associated with an element of the gear train, a manually operable driving wheel, and means effective to operatively connect the electric motor to the second shaft while simultaneously disconnecting the manually operable wheel from the third shaft, and to operatively connect said wheel to this latter shaft while simultaneously disconnecting the motor from the second shaft.

4. A driving mechanism for rolling doors, comprising a rotatable door shaft, a speed reducing gear train drivingly associated with said door shaft, a second rotatable shaft carrying means for driving said gear train, to effect rotation of the door shaft at a reduced rate relative to second shaft, an electric motor, a manually operable driving wheel, and means effective to operatively connect the electric motor to said second shaft, while simultaneously disconnecting the manually operable wheel therefrom, and to operatively connect this latter to the second shaft while simultaneously disconnecting the motor therefrom.

5. A driving mechanism for rolling doors, comprising a rotatable door shaft, a gear train drivingly associated with said door shaft, a second rotatable shaft, means on said second shaft for

driving said gear train in the rotation of the shaft, a power driven pulley and a manually operable driving wheel loose on said second shaft, and a clutch rotatable with the second shaft and 5 selectively actuatable into engagement with either one of the pulley and wheel to connect the same with the second shaft for rotation therewith, thereby selectively permitting power and hand operation of the door shaft through the single gear train aforementioned.

6. A driving mechanism for rolling doors, comprising a rotatable door shaft, a gear train drivingly associated with said door shaft, a second rotatable shaft, means on said second shaft 15 for driving said gear train in the rotation of the shaft, a power driven pulley and a manually operable driving wheel loose on said second shaft, a clutch rotatable with the second shaft and means for selectively displacing said clutch into engagement with either one of the pulley and wheel to connect the same with the second shaft for rotation therewith, thereby selectively facilitating power and hand operation of the door shaft through the single gear train aforementioned.

7. A driving mechanism for rolling doors, comprising a rotatable door shaft, a gear train drivingly associated with said door shaft, a second rotatable shaft for driving said gear train, a pulley loose on said second shaft, an electric motor for driving said pulley, a third rotatable shaft drivingly associated with an element of said gear train, a manually operable driving wheel loose on this latter shaft, a clutch on the second 30 shaft, a further clutch on the third shaft, said clutches being rotatable with the shafts on which they are mounted and being actuatable into engagement respectively with the pulley and the manually operable driving wheel to cause the 35 same to rotate conjointly with their respective shafts, and means effective to actuate the clutch mounted on the second shaft into engagement with the pulley, to facilitate power operation of the door shaft, while simultaneously disengaging the clutch mounted on the third shaft from the manually operable driving wheel, and to 40 actuate the last mentioned clutch into engagement with the wheel, to facilitate hand operation of the door shaft, while simultaneously disengaging the clutch mounted on the second shaft from the pulley.

8. A driving mechanism for rolling doors, comprising a rotatable door shaft, a speed reducing gear train drivingly associated with said door shaft, a second rotatable shaft, gear means carried by said second shaft for driving said gear train, in the rotation of the shaft, a manually operable driving wheel and a pulley loose on the second shaft, an electric motor for driving said 50 pulley, a clutch mounted on the second shaft for rotation therewith, intermediate said wheel and said pulley, said clutch being reciprocable on its shaft to selectively engage either one of said pulley and wheel to connect the same to the second shaft for rotation therewith, thereby selectively facilitating power and hand operation of the door shaft through the single gear train aforementioned, and means for reciprocating said clutch.

9. In a rolling door construction, a rotatable door shaft, a reversible electric motor, gear means operatively connectable to said electric motor for driving said door shaft in opposite directions, means for shutting off the motor, and 75 means effective in the rotation of the door shaft

in either direction to actuate said means for shutting off the motor upon completion of a predetermined number of revolutions of the door shaft and means automatically operative to brake the door shaft simultaneously with the actuation of the means for shutting off the motor.

10. In a rolling door construction, a rotatable door shaft, a speed reducing gear train drivingly associated with said door shaft, a pulley operatively connectable to said gear train, a reversible electric motor for driving said pulley, to rotate said door shaft through said gear train in opposite directions at a reduced rate relative to the motor, a brake associated with said pulley, means for shutting off the electric motor, means effective in the rotation of the door shaft in either direction to actuate said means for shutting off the motor upon completion of a predetermined number of revolutions of the door shaft, and means for automatically actuating said brake associated with the pulley simultaneously with the actuation of the means for shutting off the motor.

11. In a rolling door construction, a rotatable door shaft, a speed reducing gear train drivingly associated with said door shaft, a pulley operatively connectable to said gear train, a reversible electric motor for driving said pulley to rotate said door shaft through said gear train in opposite directions at a reduced rate relative to the motor, a brake associated with said pulley, means for shutting off the electric motor, means effective in the rotation of the door shaft in either direction to actuate said means for shutting off the motor upon completion of a predetermined number of revolutions of the door shaft, and means including an electromagnet for automatically actuating said brake associated with the pulley simultaneously with the actuation of the means for shutting off the motor.

12. In a rolling door construction, a rotatable door shaft, a speed reducing gear train drivingly associated with said door shaft, a pulley operatively connectable to said gear train, a reversible electric motor for driving said pulley to rotate said door shaft through said gear train in opposite directions at a reduced rate relative to the motor, a brake associated with said pulley, a pair of switches, each of said switches being adapted, upon opening, to shut off the motor, means effective in the rotation of the door shaft in either direction to open one of said switches, to shut off the motor, upon completion of a predetermined number of revolutions of the door shaft, and means for automatically actuating said brake associated with the pulley simultaneously with the actuation of the means for shutting off the motor.

13. In a rolling door construction, a rotatable door shaft provided with a coaxial extension rotatable therewith, a reversible electric motor, gear means operatively connectable to said electric motor for rotating said door shaft in opposite directions, a pair of switches, each of said switches being adapted, upon opening, to shut off the motor, a member mounted on said extension of the door shaft and adapted to reciprocate thereon during the rotation of the door shaft in opposite directions, and means operated by said member in the reciprocation thereof to open one of said switches upon completion of a predetermined number of revolutions of the door shaft in either direction.

14. In a rolling door construction, a rotatable door shaft provided with a coaxial extension ro-

5 tatable therewith, a reversible electric motor, gear means operatively connectable to said electric motor for rotating said door shaft in opposite directions, a pair of switches, each of said switches being adapted, upon opening, to shut off the motor, a member mounted on said extension of the door shaft for reciprocation thereon during the rotation of the door shaft in opposite directions, a pair of rockable levers associated with said switches and operable to open the same, and cam means carried by said member, said cam means being adapted, in the reciprocation of the member, to engage one of said levers and rock the same to open one of the switches upon completion of a predetermined number of revolutions of the door shaft in either direction.

10 15. In a rolling door construction, a rotatable door shaft, a threaded shaft secured to said door shaft for rotation therewith, a reversible electric motor, gear means operatively connectable to said electric motor for rotating said door shaft in opposite directions, a pair of switches, each of said switches being adapted, upon opening, to shut off the motor, a member mounted on said threaded shaft, means for causing said member to reciprocate on said threaded shaft during the rotation of the door shaft in opposite directions, means operated by said member in the reciprocation thereof to open one of said switches, to shut off the motor, upon completion of a predetermined number of revolutions of the door shaft in either direction, and means fixed on the threaded shaft adapted to engage said member simultaneously with the opening of the switch to prevent further rotation of the threaded shaft, thereby braking the door shaft.
